UNITED STATES PATENT OFFICE.

FRANK L. DOW, OF CAMDEN, NEW YORK, ASSIGNOR TO FRISBIE & STARSFIELD, OF SAME PLACE.

AUTOMATIC BELT-SHIFTER.

SPECIFICATION forming part of Letters Patent No. 326,633, dated September 22, 1885.

Application filed January 30, 1885. (No model.)

To all whom it may concern.

Be it known that I, FRANK L. Dow, of the village of Camden, in Oneida county, and State of New York, a citizen of the United States, have invented a new and useful Improvement in an Automatic Belt-Shifter; and I do hereby declare the following to be a full, clear, and exact description of the same, reference being had to the accompanying drawings, and to the letters and figures marked thereon.

My invention relates to an improvement in an automatic belt-shifter, and is designed to furnish an accurate and reliable means of shifting belts from the tight to the loose pulley, and is adapted to be used on any machinery using such pulleys where the belt is required to be shifted and the machinery stopped at regular and exact intervals; and it consists in the mechanism and mechanical movements hereinafter more fully described and claimed.

In the accompanying drawings, Figure 1 represents a side view of my automatic belt-shifter, taken at line $x x$, Fig. 3. The broken lines indicate a portion of the sprocket-wheel removed, showing the machine in the position it would be when the belt is running on the tight pulley, and showing the pawl working on the face of the ratchet-wheel. Fig. 2 is the same view showing the machine in the position it would be when the belt is running on the loose pulley, and showing the pawl raised from the face of the ratchet-wheel. Fig. 3 represents an end view of my automatic belt-shifter, showing its position when the belt is running on the tight pulley. Fig. 4 is the same view showing the position when the belt is shifted to the loose pulley. Fig. 5 is a section of the ratchet and sprocket wheels. Fig. 6 is an end view of the same. Fig. 7 is a side view of the movable belt-shifter. Fig. 8 is a top or plan view of the same. Fig. 9 is an end view of the same. Fig. 10 is a side view of the pawl which works on the ratchet-wheel. Fig. 11 is a top view of the same. Fig. 12 is a side view of a weighted dog. Fig. 13 is a top view of the same.

Having described my invention in reference to the figures illustrated in the accompanying

drawings, I will now proceed to describe the same in reference to the letters marked thereon, in which similar letters of reference refer to corresponding parts throughout the several views.

F represents the frame carrying the machine, which may be attached to the frame of any machine to which my invention is applicable.

A A represent a tight and loose pulley mounted on shaft a.

a' represents a cam rigidly attached to shaft a.

An eccentric on the shaft may be substituted without interfering with the usefulness of my invention.

a² is a forked lever working on cam a'. This forked lever is pivoted to the frame at a³.

a⁴ represents a pawl pivoted to the lower end of the forked lever a². This pawl works on the face of the ratchet-wheel a⁵, the ratchet being worked by the cam and lever before mentioned.

Attached rigidly to the ratchet-wheel is a sprocket-wheel, a⁶, which moves the endless linked belt, the sprockets fitting the links.

a⁶ represents the endless linked belt which fits in the groove on the sprocket-wheel, as shown in Fig. 6. This endless linked belt is made the desired length to give the required time and distance the machine is to run before the belt is shifted.

a⁸ represents a projection on the links of the endless belt for engaging the weighted dog.

b represents the weighted dog pivoted to the lower end of an arm. This dog is weighted to keep it in proximity to the moving belt to engage the projection a⁸ on the chain for raising the pawl and releasing the movable belt-shifter, as hereinafter more fully described.

C, Fig. 7, represents a reciprocating belt-shifter moving in or on ways attached to the frame.

c' is a shoulder or stop on the upper surface of C. This belt-shifter carries two projecting pins, c² and c³, so located as to allow the belt to move between them.

c¹⁰, Figs. 1 and 2, represents a projecting handle to move the belt to the tight pulley.

c¹¹, Figs. 1, 2, and 9, represents an inclined

projection on the shifter to engage the projection on the pawl for raising the same to disengage it from the ratchet-wheel.

c⁴ is a lever, one end pivoted to the frame at 5 *c⁵*, and the opposite end to an arm at *c⁶*.

c⁷ represents the arm which carries the weighted dog *b* pivoted to the end at *c⁸*.

c⁹ represents a connecting-rod, one end pivoted to the frame and the opposite end to the 10 lower end of arm *c⁷* at *c⁸*. The ratchet and sprocket wheels are pivoted to the frame at *c²*.

d represents a projection on the pawl to engage the incline *c¹¹* on the belt shifter for raising the pawl when the shifter is moved inwardly. 15

S is a spring for moving the shifter inwardly, as hereinafter described.

Operation: The machine being in motion in the position shown in Fig. 1 continues in motion until the projecting stop *a⁸* strikes the weighted dog *b*, which it engages, thereby raising arms *c⁷* and *c⁴*, which raise the latter from the shoulder *c¹* on the belt-shifter *C*, which is drawn inwardly by spring *S*, the incline *c¹¹* raising the pawl *a⁴* from the face of the ratchet-wheel *a⁵*, thereby shifting the belt to the loose pulley and bringing the machine to a stop. To put the machine in motion, the operator draws the belt-shifter *C* by means of 5 *o* handle *c¹⁰* outwardly until the lever *c⁴* drops back of shoulder *c¹*, thereby allowing the pawl *a⁴* and weighted dog *b* to drop into position, where they remain until the projection *a⁸* on the endless link-belt *a⁶* strikes and raises the dog *b* and connecting mechanism, thereby allowing the spring *S* to move the belt-shifter *C*, shifting the belt, and stopping the machine.

What I claim as new, and desire to secure by Letters Patent, is—

1. The combination of a belt-shifter moved by an elastic connection, an endless link-belt moved on a sprocket-wheel, the belt constructed to disengage the belt-shifter, a lever working on and driven by an eccentric or cam on the shaft for moving the endless belt, and a dog pivoted to the lever and working on the ratchet-wheel for moving the link-belt, combined and arranged, substantially as described, for shifting of the belt and stopping the machine at stated intervals. 40

2. The combination of a movable belt-shifter, an endless link-belt moved on a ratchet and sprocket wheel, and a lever moved by a cam or eccentric carrying a dog working on the ratchet-wheel for moving the same, the endless link-belt constructed to disengage the belt-shifter at regular intervals for shifting the belt from the fast to the loose pulley, substantially as described. 50

3. The herein-described belt-shifter having the following combination: a belt-shifter moved by elastic connection, an endless link-belt, a ratchet and sprocket wheel, and a pawl to move the sprocket-wheel driven by an eccentric or cam, constructed and arranged to operate the belt-shifter at fixed periods to stop the machine, arranged substantially as described. 60

FRANK L. DOW.
